UNITED STATES PATENT OFFICE

1,939,931

RAILWAY CAR STRUCTURE

William J. Tangerman, Hammond, Ind., assignor
to Union Metal Products Company, Chicago,
Ill., a corporation of Delaware

Application April 25, 1932. Serial No. 607,325

5 Claims. (Cl. 105—406)

The invention relates to railway cars and more particularly to open top gondola or hopper cars and the object of the invention is to increase the cubical capacity of the car without increasing the length, width or height of the car and with practically no increase in weight of the car.

Another object is to provide a car of such increased cubical capacity that will discharge the load of the car when dumped in a tipple.

10 My invention is especially adopted to old or existing cars wherein it is necessary to remove and replace the old end wall on account of corrosion because, in such cases, the corner post and end post are usually retained in the car and 15 my improved end wall may be punched with holes registering with the holes in the car so that it is interchangeable with the old end wall, thus my arrangement increases the cubical capacity of the car without any alteration of the 20 car itself. The construction is also adaptable to new cars and to gondola, as well as hopper cars.

In the drawing:

Figs. 1, 2 and 3 show a typical railway hopper car incorporating my improved construction, 25 wherein Fig. 2 is a section on line 2—2 of Fig. 1, and Fig. 3 is a section on line 3—3 of Fig. 1.

Figs. 4, 5 and 6 show a modified form, wherein Fig. 5 is a section on line 5—5 of Fig. 4, and Fig. 6 is a top plan view of Fig. 4.

30 The drawing illustrates a standard hopper car having spaced apart side walls 2, a sloping floor 3 between the side walls and an end wall 4 extending between the side walls from the floor to the top of the side walls and connected thereto.

35 The usual stiffening members at the tops of the side (6) and end (7) walls, respectively are shown. The end stiffener 7 projects outwardly from the car so as not to retain part of the loading when the car is turned upside down in a

40 tipple. The corner post 9 forms a connection between the side and end walls and extends downwardly to and is supported by the under-frame of the car. The end post 10 is secured to the end wall 4 and also extends to the under-frame so as to support the floor and end wall.

45 In my improvement the central portion of the end wall 4 is embossed or bulged outwardly, which central portion 13 is preferably in substantially the same plane as the outer part of the end stiffener 7, whereby the cubical capacity of the car is increased without increasing the length of the car. Obviously neither the height nor width has been affected by this improved construction.

55 The end wall 4 is preferably provided with

marginal portions 15—16—17 in substantially a single plane, which portions are connected to the corner posts 9, top stiffener 7 and floor 3, respectively. This makes a very simple pressing for a metallic plate between reciprocating dies. 60

The bulged central portion 13 is connected to the marginal portions by webs 20—21—22 which are inclined so that the car will discharge its load when turned upside down (or nearly so) in an unloading machine or tipple, as it is called. 65 The slope of the upper inclined portion 20 is preferably made less than the other inclined portions so as to assure the car clearing its load.

In the modification shown in Figs. 4, 5 and 6 the lower part of the bulged portion 40 comprises a web 42, which is substantially parallel to the floor 44 and is secured thereto. This arrangement further increases the cubical capacity of the car. The member 46 forms a support for the floor 44 and also a means for 70 attaching the end posts 48.

In the modified form the middle 49 of the end wall, is above the tops 50 of the side walls 52 and slope downwardly therefrom to the opposite side walls 52. By this arrangement the load in the car may be heaped from end to end of the car. The upper margin 54 of the outwardly bulged portion 40 extends up into the part of the end wall above the side walls and preferably conforms substantially to the contour of the top 75 of the end wall.

The upper part of the end wall is bent to form a flange 58 which increases in width toward the respective side walls and is secured thereto so as to form gussets and form a very stiff upper margin of the end wall. The outwardly projecting stiffener 60 may be used which preferably conforms to the contour of the top of the end wall and is secured to the side walls of the car. 90

The accompanying drawing illustrates the preferred form of the invention, though it is to be understood that the invention is not limited to the exact details of construction shown and described, as it is obvious that various modifications thereof, within the scope of the claims, will occur to persons skilled in the art. 95

I claim:

1. In an open top railway car having spaced apart side walls, a sloping floor between said walls, and an end wall extending between the side walls, the central portion of the end wall between the side walls being bulged outwardly so as to increase the cubical capacity of the car, the lower part of said bulged portion comprising 105 110

- a web substantially parallel to and secured to said floor.
2. In an open top railway car having spaced apart side walls, a floor, and an end wall extending between the side walls with a part thereof higher than the side walls, the central portion of the end wall including said part being bulged outwardly so as to increase the cubical capacity of the car, the upper margin of the end wall provided with an inwardly projecting flange which increases in width toward the side walls and is secured thereto to form a stiffener for the upper part of the end wall. 80
- 10 3. In an open top railway car having spaced apart side walls, a floor, and an end wall extending between the side walls with a part thereof higher than the side walls, the central portion of the end wall including said part being bulged outwardly so as to increase the cubical capacity of the car, the upper margin of said bulged portion substantially conforming to the top of the end wall. 85
- 15 4. In an open top railway car having spaced apart side walls, a floor, and an end wall extend- 90

ing between the side walls with a part thereof higher than the side walls, the central portion of the end wall including said part being bulged outwardly so as to increase the cubical capacity of the car, the upper margin of the end wall provided with an inwardly projecting flange which increases in width toward the side walls and is secured thereto to form a stiffener for the upper part of the end wall. 95

5. In an open top railway car having spaced apart side walls, a sloping floor between said walls, and an end wall extending between the side walls with a part thereof higher than the side walls, the central portion of the end wall being bulged outwardly so as to increase the cubical capacity of the car, the lower part of said bulged portion comprising a web substantially parallel to and secured to said floor. 100
